UNITED STATES PATENT OFFICE.

JAMES HUBER, OF PHILADELPHIA, PENNSYLVANIA, ASSIGNOR TO VICKERS LIMITED,
OF WESTMINSTER, LONDON, ENGLAND.

CONTACT-MINE FIRING-GEAR.

1,319,153.

Specification of Letters Patent.

Patented Oct. 21, 1919.

Application filed February 12, 1918. Serial No. 216,814.

To all whom it may concern:

Be it known that I, JAMES HUBER, a citizen of Switzerland, residing at Philadelphia, in the county of Philadelphia and State of Pennsylvania, have invented certain new and useful Improvements in Contact-Mine Firing-Gears; and I do hereby declare the following to be a full, clear, and exact description of the invention, such as will enable others skilled in the art to which it appertains to make and use the same.

This invention relates to submarine mines and particularly to that class of mines which are exploded upon contact with a ship.

An object of the invention resides in the provision of a mine which will explode only after it has come in contact with the hull of a ship, and further in so constructing the device that the liability of the parts becoming inoperative during the period between the planting of the mine and its explosion, will be prevented.

With these and other objects in view, such as will appear as my description progresses, my invention comprises the combination and arrangement of parts as set forth in and falling within the scope of the appended claims.

30 In the drawing:

Figure 1 is a sectional view of a portion of a mine showing one embodiment of my invention applied thereto;

Fig. 2 is a plan view of the device;

35 Fig. 3 is an enlarged section of a portion of the device, the section being taken on line 3—3 of Fig. 1;

Fig. 4 is a section on line 4—4 of Fig. 1, disclosing the manner in which the operating lever is mounted;

Fig. 5 is an enlarged detail sectional view with the lever and detonator carrier in the positions they will occupy before the mine contacts with the ship;

45 Fig. 6 is a section of the lever locking element, the section being taken on line 6—6 of Fig. 2;

Fig. 7 is a plan view of a modified form of the device;

50 Fig. 8 is a vertical sectional view through the same;

Fig. 9 is an enlarged section of the contact carrying casting, the section being taken on line 9—9 of Fig. 8;

55 Fig. 10 is an enlarged sectional view.

showing the elements in the positions they will occupy before the safety ring has passed into solution, the section being taken on line 10—10 of Fig. 7, and

Fig. 11 is a horizontal sectional view on 60 the line 11—11 of Fig. 10.

Referring particularly to Figs. 1 to 6, inclusive, the mine is indicated generally by the reference character 1, and is of the usual construction. Mounted on the upper side of 65 the mine is a casting 2 which is in screw-threaded engagement with the mine at 3, and is provided with a central bore 4 which communicates at its lower end with the interior of a guide tube 5. This guide tube 70 is carried by the casting 2, and is of the form described in my co-pending application, Serial No. 216,816, filed February 12, 1918, being provided with elongated openings 6 adjacent to its lower end and being 75 in communication with the detonator receiver 7 which carries the firing pin 8. The detonator 9 is supported on a carrier 10 which is maintained in position within the guide tube 5 by a wire or other suitable 80 element 11 which is of such size and material that when sufficient pressure is applied to the carrier it will be sheared. Located in spaced relation to the carrier 10 and within the guide tube 5 is a piston 12 which 85 is disposed immediately below the bore 4 and is supported within the tube by a spring 13 which bears upon the detonator carrier 10. This spring normally is under no, or at least little compression. When the water 90 enters the tube 5 through the bore 4 in the casting 2 the piston 12 will be moved downwardly until the spring 13 is put under such compression that the wire 11 will be sheared. At this time the detonator 9 will 95 be projected forcibly downwardly and will ignite the charge upon contact with the firing pin 8.

In order that the water may be excluded from the piston 12, except after the mine 100 has contacted with a ship, I have provided an inverted cup-shaped protector 14 which is preferably of the form illustrated in the drawing, or of some similar form which will perform the function for which the 105 protector is designed. This protector is preferably formed of a frangible material and is held in place, so as to close the bore 4, by a nut 15 which clamps the flange 16 to the casting 2, a suitable washer 17 being 110

disposed between the nut and the flange. When this protector 14 is broken the water will have free access to and will operate the piston 12.

5 Extending upwardly from the body of the casting 2 are two oppositely disposed pairs of ears 18, which pairs are arranged on opposite sides of the protector 14. An arcuate lever 19 extends between the members of 10 these pairs of ears 18 and follows generally the contour of the mine, being arranged, however, in spaced relation to the mine, as clearly illustrated in Fig. 1 of the drawing. This lever is secured rigidly in place, normally by means of pins 20, which extend 15 through the ears 18 and through the lever. These pivot pins are, however, of such size and material that either one or the other, or both, may be sheared and their supporting action thus destroyed upon the application 20 of force to the lever. Depending from the ends of the lever are pivoted bills 21 which, at their points, engage the outer surface 25 of the mine to prevent the catching of cables or the like beneath the lever and the consequent fouling of the mine during its launching.

Referring particularly to Fig. 5, it will be seen that the lever 19 is provided with a 30 recess 22 into which the protector 14 extends. The provision of this recess results in the formation of teeth 23 and 24, the former being located at the sides of the protector and the latter immediately beneath 35 the same, but in spaced relation thereto.

Mounted on one ear of each of the pairs of ears, is a safety lock which comprises a cylinder 25 in which is mounted a locking pin 26. This pin is adapted to extend 40 through the adjacent ear and into the lever 19. A spring 27 encircles each of these locking pins and tends to move the same from its operative position. However, this movement of the locking pins is prevented before 45 the mine is planted by the interposition of soluble elements 28 between the ends of the locking pins and the adjacent walls of the cylinders. These cylinders 25 are provided with openings 29 through which the water 50 may have access to the elements 28 so as to cause the same to pass into solution and thus release the locking pins 26 so that they may be acted upon by the springs. It will be seen that when these pins 26 are in their 55 locking positions, the movement of the lever 19 with relation to the mine will be prevented.

After the mine has been planted, however, the elements 28 will pass into solution and 60 the springs 27 will withdraw the locking pins so that the mine will be ready to explode upon the contact of the same with the hull of a ship.

Should the one arm or the other of the 65 lever 19 contact with the hull of a ship, the

contact arm will be depressed and moved toward the face of the mine. This action is made possible because of the fact that the force tending to move the arm acting against the buoyancy of the mine will cause the shearing 70 of one of the pivot pins 20 and preferably the one adjacent to the point of application of the force. Upon the movement of the lever as described, about the other pin as a pivot, one of the teeth 23 will bite into 75 and rupture the frangible protector 14 so that water may have access to the piston 12 and operate upon the same in the manner which has been previously described. Of course, if the ship contacts with the lever 80 directly midway between the pivot pins 20, it is possible that both of the pins will be sheared and this being done, the lever will be depressed until the upper tooth 24 ruptures the protector 14 and permits the 85 entrance of water into the tube 5.

Referring to the modification of the invention disclosed in Figs. 7 to 11, inclusive, it will be noted that a substantially cylindrical casing 10' is mounted on the mine 1'. 90 The lower end of this cylinder is provided with an axial bore 11', and the wall thereof is provided with elongated slots 12'. A protector 13' of a shape somewhat similar to that illustrated in Fig. 5, is mounted so as to 95 cover the bore 11', being held in position by a nut 14'.

The upper end of the cylinder is closed by a cap 15' which is provided with a socket 16'. A ball 17' is mounted within this 100 socket and is formed on or extends from a casting or spider 18', the movement of the ball with relation to the socket being, however, normally prevented by a pin 19' which extends through the cap 15' and into the upper side of the ball 17'. This pin is of soft material and is of such size that when a certain force is applied to the spider or casting 18', the pin will be sheared. Depending 105 from the spider 18' is a fracturing tube 20' which envelopes the upper end of the protector 13'. A plurality of arms 21' extend outwardly from the spider 18' and through the slots 12' in the sides of the cylinder 10'. A circular bar or pipe 22' surrounds the 110 mine 1' and is attached to the ends of the arms 21', as illustrated in Figs. 7 and 8 particularly.

In order that the relative movement of the arms 21' to the mine may be prevented 115 during the launching of the mine, I have provided a locking ring 23', which encircles the tube 20' and closely engages the same, as well as the inner wall of the cylinder 10'. This ring 23' is supported in a raised position by means of a supporting ring 24' of 120 soluble material, with which supporting ring the locking ring is adapted to change places after the former has passed into solution, and in which position the locking ring will 125 130

- be inoperative to prevent the rocking motion of the fracturing tube 20'. Before the mine is launched the elements will be in the positions illustrated in Fig. 10, but after the 5 mine has been launched the supporting ring 24' will pass into solution and permit the locking ring 23' to drop below the lower end of the fracturing tube 25, so that so far as the locking ring is concerned, this tube is 10 free to work. When the mine is engaged by the hull of a ship, one side of the cage which is formed by the arms 21' and the connector 22, will be moved toward the face of the mine, the force being sufficient to shear the 15 safety pin 19'. When such action as this takes place, the fracturing tube 20' will rupture the protector 13' and permit the access of water to the detonator operating piston, which is disclosed at 25'. 20 It will thus be seen that the rupturing of the protector 13' during the launching of the mine will be absolutely prevented. Furthermore, this protector will not be ruptured by the effect of the water currents, but 25 only upon the contact of the mine with the hull of a ship, which contact will result in the shearing of the pin 19'.
- What I claim is:
1. The combination with a contact mine, of a firing gear therefor, which gear includes a water-pressure-operated detonator, a frangible protector excluding the water from the detonator operating mechanism, and a lever having portions thereof arranged 30 to rupture said protector, said lever being supported at two points by shearing pins.
  2. The combination with a contact mine, of a firing gear therefor comprising a water-pressure-operated detonator, a frangible 35 protector for controlling the entrance of the water to the detonator actuating mechanism, and a lever having portions thereof adapted to engage and rupture the protector, said lever being supported at two separate 40 points by pins which are adapted to be sheared upon the application of pressure to the lever.
  3. The combination with a contact mine, of a firing gear including a guide tube, a 45 water-pressure-operated detonator in said tube, a frangible protector normally excluding the water from the tube, and a lever having portions to engage and rupture the protector, said lever being supported at two 50 points by means which are adapted to be rendered inoperative to act as supports upon the application of pressure to the lever.
  4. The combination with a contact mine, of a firing gear therefor, said gear comprising 55 a tube, a water pressure operated detonator mounted in said tube, a frangible protector normally excluding the water from the tube, means to rupture said protector
- upon the contact of the mine with a ship, and means to lock said last mentioned means to prevent its operation during the launching of the mine. 65
5. The combination with a contact mine, of a firing gear therefor including a guide tube, a water-pressure-operated detonator 70 mounted in said tube, a frangible protector normally operative to exclude water from said tube, means to rupture said protector, and means to lock said last mentioned means during the launching of the mine. 75
  6. The combination with a contact mine, of a firing gear therefor including a guide tube, a water-pressure-operated detonator mounted in said tube, a frangible protector 80 normally operative to exclude water from said tube, means to rupture said protector, and means to lock said last mentioned means during the launching of the mine, said locking means being automatically rendered inoperative. 85
  7. The combination with a contact mine, of a firing gear therefor including a guide tube, a water-pressure-operated detonator mounted in said tube, a frangible protector 90 normally operative to exclude water from said tube, means to rupture said protector, means to lock said last mentioned means during the launching of the mine, said locking means being automatically rendered inoperative, and means to prevent the operation 95 of the rupturing means, except upon the application of a predetermined pressure to the rupturing means.
  8. The combination with a contact mine, of a firing gear therefor, said gear including 100 a guide tube, a water-pressure operated detonator in said guide tube, a body portion having a bore communicating with said guide tube, a frangible protector normally closing said bore and an arcuate lever supported at two points on said body portion by shearing pins, said lever having tooth portions adapted to rupture the protector upon the shearing of either or both of said pins. 105
  9. The combination with a contact mine, of a firing gear therefor, said gear including 110 a guide tube, a water-pressure-operated detonator in said guide tube, a body portion having a bore communicating with said guide tube, a frangible protector normally closing said bore and an arcuate lever supported at two points on said body portion by shearing pins, said lever having tooth portions adapted to rupture the protector upon 115 the shearing of either or both of said pins, and means to prevent the pivotal movement of the lever and the shearing of said pins during the launching of the mine. 120
- In testimony whereof I affix my signature. 125
JAMES HUBER.
